UNITED STATES PATENT OFFICE.

THOMAS H. WRIGHT, OF LOS ANGELES, CALIFORNIA.

TURNTABLE.

Application filed September 15, 1922. Serial No. 588,432.

To all whom it may concern:

Be it known that I, THOMAS H. WRIGHT, a citizen of the United States, residing at Los Angeles, in the county of Los Angeles 5 and State of California, have invented new and useful Improvements in Turntables, of which the following is a specification.

My invention relates to turn-tables, and more particularly, although not necessarily, 10 to turntables adapted for movably supporting a section of mono-rail track.

It is a purpose of my invention to provide a turn table of simple and durable construction which operates to movably support with the least possible friction a section 15 of mono-rail track so that such section, together with a mono-rail car, can be positioned to allow the car to be turned and moved onto any one of a plurality of mono- 20 rail tracks.

Although I will describe only one form of turntable embodying my invention, and will point out the novel features thereof in the claim, it is to be understood that various 25 changes and modifications may be made without departing from the spirit of the invention and the spirit and scope of the appended claim.

In the accompanying drawings,

30 Figure 1 is a view showing in top plan one form of turntable embodying my invention in applied position with respect to a plurality of mono-rail tracks;

35 Figure 2 is a vertical sectional view of the turntable shown in Figure 1 with the track section turned to a right angular position with respect to Figure 1.

40 Referring specifically to the drawings, in which similar reference characters refer to similar parts, my invention in its present embodiment comprises a base of circular form constructed of any suitable material such as concrete or the like and comprising a central portion 15 and a peripheral portion 16, the two being connected by a bottom portion 17. The central portion 15 is formed with a depending hub portion 18 provided with an opening in which is adapt- 45 ed to be journaled a king pin 19 connected

to a carriage upon which a section of mono- 50 rail track is adapted to be supported. The upper edge of the peripheral portion 16 is provided with an annular metal track 20, and similarly the upper edge of the central portion 15 is provided with an annular 55 track 21.

The carriage upon which the section of mono-rail track is supported may be of any suitable form and in the present instance comprises a plurality of transverse beams 60 22 and 23, the beams 22 being arranged adjacent each other and connected by a beam 24. The beams 23 are so disposed as to support rollers or wheels 25 so as to move over the track 20, it being particularly noted 65 that the axles of the wheels are disposed in divergent relation to each other so that the rollers can occupy proper positions upon the track 20. The beams 22 carry rollers or wheels 26 which are adapted for movement over the track 21, and to this end the axles therefor are disposed in divergent relation to each other.

70 The mono-rail track section which is supported upon the beams 22 and 23 is of the same construction as that disclosed in my copending application filed September 15th, 1922, Serial No. 588,430, and the construction of the supporting structure for the track section is such as to rigidly connect 75 the several beams 22 and 23. The king pin 19 is adapted to extend through a beam 24 comprised in the supporting structure for the track section, and it thus serves to provide a pivot for the entire carriage about 80 which the latter rotates upon the base.

85 In practice, the track section of the turntable can be moved through the medium of the carriage to occupy any desired position to connect stretches of mono-rail track 28 90 with each other or to reverse the position of the mono-rail car with respect to any one of the tracks. During movement of the carriage, the rollers 25 and 26 move over the tracks 20 and 21, respectively, and it is 95 to be particularly noted that the rollers are of frusto-conical form, while the tracks are inclined towards the axis of the table, so

that uniform traction between the rollers and tracks is secured and friction between the two reduced to a minimum.

I claim as my invention:

- 5 A turntable comprising a base formed with plastic material and including a central annular portion, a peripheral annular portion, a bottom portion connecting the two at their lower edges, and a hub portion

disposed axially of the central portion, 10 tracks on the upper edges of the central and peripheral portions, a carriage including a king pin journaled in the hub portion and rollers movable over said tracks, and a monorail supported on the carriage.

In testimony whereof I have signed my name to this specification.

THOMAS H. WRIGHT.
